UNITED STATES PATENT OFFICE.

EDWARD A. EVERETT, OF POTSDAM, NEW YORK, ASSIGNOR OF ONE-HALF TO EDWIN A. MERRITT, JR., OF POTSDAM, NEW YORK.

BOTTLE-CAPPING MACHINE.

1,085,557.

Specification of Letters Patent.

Patented Jan. 27, 1914.

Application filed March 6, 1909, Serial No. 481,708. Renewed June 11, 1913. Serial No. 773,141.

To all whom it may concern:

Be it known that I, EDWARD A. EVERETT, a citizen of the United States, residing at Potsdam, in the county of St. Lawrence and 5 State of New York, have invented certain new and useful Improvements in Bottle-Capping Machines, of which the following is a specification.

This invention relates to bottle capping 10 machines, and belongs directly in the class with machines for closing by means of paper disks receptacles, usually of cylindrical form, made of paper and used as milk containers.

15 The object of this invention is the construction and arrangement of mechanical parts whereby a disk closure is pressed into the mouth of a paper milk bottle, the edge of the disk being turned up and supplied 20 with adhesive during the pressing operation.

It is also an object of this invention to provide a crate movable independently of the machine itself, but forming an essential 25 part thereof inasmuch as the crate has holding bottle holders fashioned to receive the bottles and made sufficiently rigid to resist any injurious expansion of the bottles during the capping action of the machine parts.

To accomplish the objects set forth, the 30 parts are made and associated as illustrated in the accompanying drawings, of which—

Figure 1 represents a front view of this invention with all parts assembled. Fig. 2 is a top plan view of the disk closure, and 35 Fig. 3 is a side view thereof. Fig. 4 is a plan view of the die plate for up-setting the flanges or edges of the disk closures. This view is in part a horizontal section of the die plate on line $x-x$ of Fig. 1, and shows 40 the channels for distributing the adhesive to the perforated plates of the various openings through the plate. Fig. 5 is a side view of a portion of the machine, and shows the stops by which the crate is held in proper 45 position for the capping operation. Fig. 6 is an enlarged view of a presser head in section, and of a portion of the die plate in section, showing the parts about as they are relatively arranged at one point during the 50 capping operation. In this figure are also shown the fabric and perforated plates through which the adhesive reaches the edges of the closures. The ducts for the

escape of the air are also more clearly illustrated in Fig. 6.

The same number is employed to refer to the same part throughout the drawings and description.

Considering Fig. 1, there will be noted the two side frames or uprights 1 and 2 which support the main shaft 3. The shaft has cranks 4 and 5 to which are connected pitmen bars 6 and 7 attached at their lower ends to a cross-head frame 8. Presser heads 9 are suitably secured to the lower surface of the cross-head frame. Below the cross-head frame is arranged the die plate 10. There is some interval intentionally left between the presser heads and the die plate, because it is necessary in using this invention that the attendant shall reach all parts of the die plates to place the closures thereon. From the die plate 10 rods 11 extend vertically and pass through guiding sleeves 12 supported by the cross-head frame as illustrated. The ends of the rods 11 above the cross-head frame are provided with nuts and washers and the springs 13 encircle the ends of the rods between the washers and top of the cross-head frame. The die plate is thus cushioned against the lifting impact of the cross-head frame as it rises after each capping operation.

As best shown in Fig. 4, the die plate 10 has a number of openings through it. At 45 the top of each opening is a seat 14 constructed to receive the disk closure. Next considering Fig. 6, it will be observed that immediately below the seat 14 is placed the inwardly-tapering perforated ring 15, covering the channels 16. In Fig. 4 it is shown that the channels 16 lead to and encircle each opening through the die plate. The lower portion of each opening through the die plate is provided with a number of recesses 90 17, and these recesses are inclined correspondingly with the outwardly-tapering lower portion 18 of the opening through the die plate. The features just described will be further mentioned.

Flexible tubes 19 connect the receptacles 20 with the channels 16 in the die plate, and the receptacles may hold a quantity of any preferred adhesive, such as selected gum arabic and distilled water. It is desirable 105 that the adhesive employed shall be wholly

55

75

100

105

without unpleasant or injurious effect upon the milk, although the amount of the adhesive which by any ordinary condition of the operation might reach the milk is exceedingly small.

The disk closures 21, as illustrated in Figs. 2, 3, and 6, are composed of two layers of paper, the lower layer being the greater in diameter. It is the edge of the lower layer 10 of the disk that is turned up and sealed in the mouth of the bottle 22 as hereinafter explained.

A number of relatively rigid bottle holders 23 are suitably secured to a crate 24, movable independently of the machine on the table thereof 25, and between the uprights 1 and 2. In Fig. 1 it is set out that the crate fits the interval between the uprights. When moved upon the table and passed between 20 the uprights the position of the crate is thus fixed so far as its displacement sidewise is concerned. It is necessary in addition to conveniently and accurately locate the crate with respect to its position on the table, in 25 order that it may be moved far enough between the uprights but not too far. The parts immediately concerned in thus additionally positioning the crate are best shown in Fig. 5, and comprise the fan-shaped stop 30 plates 26 and 27, both secured to and adapted to be raised by the rock-shaft 28. When the crate is in the proper place projecting as far as designed in front and in rear of the uprights, the stops 26 and 27 may be raised by 35 pressing the treadle 29 downwardly. But, if the crate is not exactly in its proper place, readily determined after a slight acquaintance with the working of this invention, and projects too far either in front or in 40 rear of the uprights, stops 26 and 27 cannot be raised. In other words, unless the crate is accurately in position to hold the bottles in the necessary attitude with regard to die plate 10, this invention cannot be started, 45 for, the treadle 29 also actuates the belt-shifter 30, moving the power belt 31 from the idle pulley 32, to the fixed pulley 33 thereby driving shaft 3 by means of belt 34.

The remaining elements of this invention 50 may be most clearly explained in connection with the statement of the mode of operation.

Let it be assumed that the seats 14 of the openings through the die plate 10 have each received a disk 21 from the hands of the 55 attendant, that the crate is in proper position and the mechanism started. In passing over inwardly-tapering perforated plate 15 the edge of the disk will be turned up as illustrated in Fig. 6, and its surface will 60 wipe a film of adhesive from the plate. Under any circumstances, the now cup-formed disks are pressed by the heads 9 into close contact with the mouths of the bottles, and the film of adhesive adds to the 65 completeness of the sealing, and, further-

more secures the disks in place. After a few minutes, the bottles may be turned up-side-down and the milk will be all retained for any length of time. As the mechanism starts, the die plate 10 descends and the outwardly-tapering surface 18 engages the upper edge of the bottle and centers the bottle for the action of the presser head 9. The shoulder 18^a at the top of the tapering wall 18, acts as a limiting means projecting into 75 the opening to permit the entrance of the bottle into the opening a certain distance only. As the disk is forced downwardly the air beneath it escapes by way of ducts 17. The positions and extent of ducts 17 are 80 best shown in Fig. 6, and the escaping air flows over the edge of the bottle into the ducts as indicated by the arrows. When the capping operation is complete, the foot is taken from treadle 29, and the tendency 85 of the weighted arms 35, loose on shaft 3, is to resume the positions shown in Fig. 1 and to raise the sliding plate 36 working in the guides 37, as illustrated in Fig. 1. The sliding plate is secured to the cross-head frame 8 as also shown. This movement is permitted by reason of the fact that the weights 38 on the pivoted arms that supported the treadle, raise the treadle to its highest position and move the power belt 31 back to the idle pulley 32. The parts now come to rest in the positions illustrated in Fig. 1, the die plate being raised from the bottles, and the crate may be removed to give place to another.

While some pressure unavoidably results during this operation upon the walls of the bottles, as milk is relatively incompressible by the devices herein set forth, the bottles are constructed to closely fit the holders 23, and the holders are intentionally of sufficient strength to withstand the pressure and support the wall of the bottle in each.

Again considering Fig. 6, there will be noted within the channel 16 and against the 110 perforated annular plate 15, a band of fabric 39. The function of this piece of fabric is to prevent the too rapid exudation of the adhesive. Incidentally, the fabric acts to filter the adhesive and to prevent the passage of small solid particles which might get between the contacting surfaces of the disk and bottle and permit leakage.

Having now described this invention and explained the mode of its operation, what 120 I claim is:—

1. In a bottle capping machine, the combination with a supporting table, of a removable crate carried by the table, bottle holders borne by said crate, each of said 125 holders being constructed to receive one of the bottles and to closely fit the bottle externally all around, each of said holders having relatively rigid walls whereby the bottle is reinforced to resist internal fluid pres- 130

sure, and means including presser heads constructed to press caps into the mouths of the bottles.

2. In a bottle capping machine, the combination with a supporting table, of a removable crate carried by the table, bottle holders borne by said crate, each of said holders being constructed to receive one of the bottles and to closely fit the bottle all around, each of said holders having relatively rigid walls whereby the bottle is reinforced to resist internal fluid pressure, means including presser heads constructed to press caps into the mouths of the bottles, and positioning devices connected with the table and constructed to retain said crate in a predetermined position upon the table.

3. In a bottle capping machine, the combination with presser heads and means for operating them, of a support for the vessels to be capped, a die plate movable toward and from said support, the die plate having openings constructed to admit the mouths of the vessels to be capped, the said die plate having portions projecting into the said openings and adapted to limit the distance that the vessels enter the openings, and the walls of said openings having ducts communicating with the openings above the said limiting means and affording passages for the escape of air as the vessel is capped.

4. In a paper bottle capping machine, the combination with presser heads and means for operating them, of a support located below the presser heads, removable bottle holders arranged upon the said support in the paths of the presser heads, the said bottle holders having relatively unyielding walls constructed to fit the bottles exteriorly and adapted to prevent the expansion thereof by internal pressure, positioning devices fashioned and disposed to locate the bottle holders under the presser heads, and devices connected one with another and arranged to be operated together for actuating the said positioning devices and for applying power to the means for operating the presser heads.

5. In a bottle capping machine, the combination with means constructed to insert a cap in a paper bottle containing a relatively incompressible fluid, of a die plate arranged below the cap-inserting means and constructed to upset the edge portions of the caps, a removable device supported below the cap-inserting means, a plurality of bottle holders arranged upon said removable device whereby the paper bottles may be held in position to be capped, the said bottle holders having open tops to receive the bottles and closed bottoms, the said holders having the same shape as the bottles and having also relatively unyielding walls constructed to

fit the bottles closely and to prevent their expansion by internal fluid pressure.

6. In a machine for capping paper bottles, the combination with presser heads and means for operating them, of devices arranged in the paths of the presser heads and constructed to apply adhesive to the flanges of paper caps acted upon by the said presser heads.

7. In a machine for capping paper bottles, the combination with presser heads and means for operating them, of devices arranged in the paths of the presser heads and adapted to upset the edge portions of paper caps acted upon by the said presser heads, the said devices being also constructed to apply adhesive to the said edge portions of the caps.

8. In a bottle capping machine, the combination with presser heads and means for operating them, of a movable die plate provided with openings each opening being surrounded by an upper inwardly-tapering perforate surface, the said die plate being provided with communicating channels extending around the said openings severally, the perforations of said tapering surface opening into the channels.

9. In a bottle capping machine, the combination with presser heads and means for operating them, of a movable die plate provided with openings each opening being surrounded by a perforate surface, the said die plate being provided with communicating channels extending around each of the said openings, and the perforations of the said surface opening into the channels.

10. In a machine for closing vessels, the combination of a reciprocating closure inserting and shaping means; and means associated with said shaping means for applying an adhesive to the closure during the inserting operation.

11. In a machine for closing vessels, the combination of a reciprocating closure inserting and shaping means comprising a hollow ring shaped die, and means associated with said shaping means for applying an adhesive to the closure during the inserting operation.

12. In a machine for closing vessels, the combination of a reciprocating plunger; a reciprocating hollow shaping die through which said plunger passes provided with an opening; and means to supply an adhesive to the inside of said hollow die.

In testimony whereof I affix my signature in presence of two witnesses.
